UNITED STATES PATENT OFFICE.

ARTHUR C. HAYDEN, OF BROCKTON, MASSACHUSETTS.

SUPPORT FOR RADIO APPARATUS.

Application filed December 13, 1926. Serial No. 154,394.

The invention to be hereinafter described relates to radio apparatus, and more particularly to a portable stand for supporting the essentials of a radio receiving set, with the exception of the aerial and ground, the construction being such that the receiver may be conveniently supported so that the dials and other devices on the receiver can be readily adjusted by one when in recumbent position.

Frequently a person may desire to enjoy the comfort and rest of being in bed and at the same time listen to radio programs; this is particularly true late in the evening when distant broadcasting stations are more easily brought in. The present apparatus lends itself advantageously to this use.

An important field for the apparatus is in hospitals. The stand may be quickly and easily placed at the side of the bed of a patient, where he may enjoy the entertainment and beneficial effect of listening in, and by the use of head phones there will be no noise of the radio in the room which might be disturbing to others.

The character of the invention may be best understood by reference to the following description of one good form thereof shown in the accompanying drawings, wherein:

30 Fig. 1 is a perspective view of apparatus embodying the invention;

Fig. 2 is an end view of the radio receiver and its clamp for connecting the same with the horizontal bar of the stand, and 35 angular adjustment of the receiver being shown in dotted lines;

Fig. 3 on an enlarged scale is a view partly in elevation and partly in section of the reel and its supporting bracket;

40 Fig. 4 on an enlarged scale is a plan of the battery carrier and batteries thereon; and

Fig. 5 is a vertical section through the upper portion of the post.

45 Referring to the drawings, a stand (Fig. 1) comprises a post 1 having an upper member 3 and a lower member 5 in telescopic relation, the upper member being adjustable vertically in the lower member. It may be secured in its different positions of adjustment by a pin 7 entered through a hole in the upper end of the lower member 5 and adapted to enter any one of several holes 9 in the upper member. Pivotal connected to the lower end of the post are four legs 11 having

rubber tips 13 at the lower ends thereof. Projecting up from the pivotal points of the legs are arms 15 having rubber tips 17 at the upper ends thereof adapted to press against the post. Hand screws 19 are entered loosely through holes in the arms and are threaded into the post, the construction being such that the hand screws may be screwed into the post so as to tightly press the rubber tips 17 against the post and compress the tips somewhat. By this construction and arrangement the leg rubber tips 13 may be caused to cooperate with the arm rubber tips and with the post, thereby to give the legs a secure grip on the floor which will hold the post in stable position. The post and the legs described may be substantially the same as disclosed in my copending application Serial No. 137,858, filed September 27, 1926.

50 A stud 21 (Fig. 5) is swivelled in the upper end of the member 3 of the post, and at the top of the stud is a head which rests on the top of the member 3, said head being formed to provide a clamp 23 having a hand screw 25 for tightening the same.

55 Secured in the clamp is a tubular horizontal bar 27 having a long arm 29 and a short arm 31. A radio receiver 33 has a clamp 35 provided with a hand screw 37 and adapted to be secured to the long arm 29. The construction is such that when the clamp is loosened the receiver may be adjusted longitudinally of the bar to different positions, and also the receiver may be adjusted 60 about the axis of the bar so that the front face of the receiver will be inclined more or less to the vertical. It may be set to a position such that the dials and other devices may be readily seen and adjusted by a person when in recumbent position.

65 Secured to the short arm 31 of the bar at the opposite side of the post from the receiver, is a battery carrier 39 comprising a disk-shaped base 41 and a post 43 having a clamp 45 provided with a hand screw 47 whereby the post may be secured to the bar. Rising from the base 41 are pins 49 for positioning the batteries thereon. In the present instance the carrier is shown supporting three A batteries 51 and a B battery 53.

70 The clamps for the receiver and the battery carrier permit them to be adjusted longitudinally of the bar so that they substantially balance each other, or this may be ac- 110

complished by adjusting the bar longitudinally in the post clamp 23. It is desirable that the wires leading from the battery to the receiver may be conducted from the former to the latter with protection and without liability of entanglement with other parts of the apparatus. To accomplish this the wires from the battery are threaded through a lateral hole 55 in the tubular bar adjacent the battery carrier, are conducted through the bar and emerge therefrom through a lateral hole 57 in the bar adjacent the receiver. They are led thence to and connected to binding posts 59 on the receiver.

Provision is made for accommodation of extension wires for connection with the aerial and ground. To accomplish this, a reel 61 (Figs. 1 and 3) is provided having heads 63 and 65 on a hub 67 mounted on a shaft 69 carried by a bracket 71 having at the upper end thereof a clamp 73 provided with a hand screw 75, said clamp being adapted to be secured in different positions of adjustment on the horizontal bar. The reel head 63 is provided with a handle 77 which may be grasped by the operator to wind the wires on the reel. The aerial and ground extension wires may be side-by-side in the same covering and may extend through a hole 79 in the head 63, the ends of said wires being adapted to be connected to terminals 81 (Fig. 1) on the receiver. A knot may be made in the wires to prevent them from being pulled inward through the hole 79 in the head 63. These wires may be of substantial length, such, for example, as 50 feet, and at ends thereof clips 85 may be provided for connection with the aerial and ground. When the extension wires are not in use, the clips may be attached to the head 63, as shown in Fig. 1.

It is desirable that the reel shall have provision for permitting and preventing rotation thereof. To accomplish this, a hand nut 87 (Fig. 3) is threaded onto the end of the shaft 69. It may be tightened to confine the reel hub 67 between the bracket 71 and the nut, or it may be loosened to permit rotation of the reel as desired. After the extension wires have been wound on the reel, it is desirable that the latter shall be locked against rotation in order to prevent loose convolutions of the wires on the reel.

Usual head telephones 89 may be provided connected by wires 83 with clips 85 on the receiver, two of such phones being shown herein. When these head telephones are not in use, they may be hung on the horizontal bar as shown in Fig. 1.

When it is desired to use the apparatus, the stand may be placed at the side of the chair or the bed of the user, the nut 87 may be released, and the clips of the terminal wires may be detached from the reel head

63. The wires may be unwound from the reel to a sufficient extent to enable the clips to be connected with the aerial and ground. Then the hand nut 87 may be tightened to prevent rotation of the reel. Before unwinding the extension wires, the ends thereof should be disconnected from the receiver terminals 81. After the wires have been unwound to the desired extent, the ends thereof may be connected again to said terminals. Now it only remains for the user to place the head phones on his head and adjust the dials and other controls on the receiver to tune in the stations desired. The swivel stud 21 enables the horizontal arm to swing about the vertical axis of the post. The long arm of the bar may extend partially across the bed and support the receiver conveniently in front of the person in bed. As stated, the receiver may be tilted about the horizontal axis of the bar and clamped in position to facilitate visualization and adjustment of the dials by the operator. When it is desired to discontinue listening in, the operator may remove the head telephones from his head, hang them on the horizontal bar, and swing the receiver and the bar about the vertical axis of the post so that they will be out of the way at one side of the bed.

The upper member of the post may be adjusted longitudinally of the lower member of the post and be held by the pin 7 at the elevation desired. When the apparatus is not in use, the horizontal bar carrying the radio receiver, the battery carrier and reel may be removed from the post by lifting the stud 21 from the upper member thereof. The assembled parts thus removed may be conveniently stored beneath the bed if desired.

Claims—

1. Radio apparatus comprising, in combination, a stand having a post, a horizontal bar secured intermediate its ends to the post, a radio receiver secured to the bar at one side of the post and a battery carrier secured to the bar at the opposite side of the post, a bracket secured to the bar, and a reel on the bracket having extension wires thereon, one for connection with the aerial and the other for connection with the ground.

2. Radio apparatus comprising, in combination, a stand having a post, a bar secured to the post having long and short arms projecting in opposite directions from the post, a radio receiver having a clamp secured to the long arm, and a battery carrier having a clamp secured to the short arm.

3. Radio apparatus comprising, in combination, a stand having a post, a tubular bar secured to said post and having arms projecting in opposite directions from the post, a radio receiver secured to one of the arms, and a battery carrier secured to the other

arm, said tubular bar being adapted to receive wires extending from the batteries on the carrier to the receiver.

4. Radio apparatus comprising, in combination, a stand having a post, a tubular horizontal bar secured to the post and having spaced lateral holes therein, and a radio receiver and a battery carrier secured to the bar at opposite sides of the post, said tubular bar and the lateral holes therein being adapted to have wires threaded therethrough leading from the batteries to the receiver.

5. Radio apparatus comprising, in combination, a stand having a post, a horizontal bar secured to the post intermediate the ends thereof, and a radio receiver and a battery carrier secured to the bar at opposite sides of the post, said receiver being provided with a clamp for securing the receiver to the bar in different positions of adjustment about the axis of said bar.

6. Radio apparatus comprising, in combination, a stand having a post with upper and lower telescoping members, means to secure the upper member to the lower member in different positions of vertical adjustment, a bar secured to the upper member, and a radio receiver and battery carrier secured to the bar at opposite sides of the post.

7. Radio apparatus comprising, in combination, a stand having a post, a stud swivelled in the post, a bar secured to the

stud and a radio receiver and battery carrier secured to the bar at opposite sides of the stud.

35

8. Radio apparatus comprising, in combination, a stand having a post provided with a clamp at the upper end thereof, a bar secured in the clamp, and a radio receiver and battery carrier secured to the bar at opposite sides of the post, said bar being adjustable longitudinally through the clamp.

9. Radio apparatus comprising, in combination, a stand having a post, a bar secured to the post, a radio receiver and a battery carrier secured to the bar at opposite sides of the post, a bracket secured to the bar having a shaft, a reel on the shaft for receiving extension wires adapted for connection with the ground and aerial, and means for permitting or preventing rotation of the reel on the shaft.

45

10. Radio apparatus comprising, in combination, a stand having a post, a bar secured to the post, a radio receiver and a battery carrier secured to the bar at opposite sides of the post, a bracket secured to the bar having a shaft, a reel on the shaft for receiving extension wires for connection with the ground and aerial, and a hand nut threaded on the shaft adjustable to confine the reel between the bracket and nut and prevent rotation of the reel.
